UNITED STATES PATENT OFFICE

1,996,765

MINING MACHINE

Morris P. Holmes, Claremont, N. H., assignor to
Sullivan Machinery Company, a corporation of
Massachusetts

Application June 9, 1931, Serial No. 543,144

38 Claims. (Cl. 262—28)

This invention relates to mining machines and more particularly to machines for cutting coal in mines.

An object of this invention is to provide an improved coal mining machine. Another object is to provide an improved mining machine of the wheel mounted, track guided type adapted to operate while supported and guided by the mine trackway. A further object is to provide improved means for propelling the machine and for operating the cutting mechanism. Still another object is to provide, in a mining machine wherein a swingable kerf cutter is employed to cut the coal, improved means for swinging the kerf cutter. Yet another object is to provide, in a mining machine of the aforesaid character, improved truck wheel driving mechanism. A further object is to provide an improved kerf cutter swinging and truck wheel driving gearing wherein separate transmission mechanisms are employed for effecting kerf cutter swing and truck wheel drive in either of opposite directions at high or low speeds and having incorporated therein improved control mechanisms. These and other objects and advantages of this invention will, however, hereinafter more fully appear.

In the accompanying drawings there is shown for purposes of illustration one form which the invention may assume in practice.

In these drawings,

Fig. 1 is a plan view of the illustrative embodiment of the improved mining machine.

Fig. 2 is a side elevational view of the machine shown in Fig. 1.

Fig. 3 is a central, longitudinally extending, vertical sectional view taken substantially on line 3—3 of Fig. 1.

Fig. 4 is a horizontal sectional view taken substantially on line 4—4 of Fig. 2.

Fig. 5 is a view similar to Fig. 4 illustrating the improved transmission gearing and its associated control mechanism, the transmission gearing being shown in plan.

Fig. 6 is a longitudinally extending vertical sectional view taken substantially on line 6—6 of Figs. 4 and 5.

Fig. 7 is a detail sectional view taken on line 7—7 of Fig. 4.

In this illustrative construction there is shown a coal mining machine of the "lowvein" arc-cutter type generally comprising a truck 1 mounted on wheels 2 adapted to run along a mine trackway 3. Mounted on this wheeled truck is a machine frame or body 4 of a low compact design having pivotally mounted thereon, at its forward

end for horizontal swinging movement relative thereto, a kerf cutter 5. This kerf cutter comprises a plane cutter bar 6 having mounted on its margin a circulating cutter chain 7. Arranged at the opposite sides of the rear portion of the machine frame are truck wheel driving and kerf cutter swinging members 8 and 9 respectively. As shown, the kerf cutter swinging member 9 is in the form of a chain sprocket and engages a loose-link chain 10. This chain is guided relative to the chain sprocket 9 by guide sprockets 11 and 12 herein arranged on axes parallel with and below the axis of the sprocket 9, while arranged at the rear corners of the machine frame are horizontal guide sprockets 13. The chain 10 passes beneath the guide sprocket 12 upwardly around the chain sprocket 9, downwardly around the guide sprocket 11 and around the rear guide sprockets 13, and the end portions of this chain extend longitudinally along the sides of the machine frame in the manner shown in Fig. 1 and are connected to a member 14 pivotally carried by a rotatable locking pin 15 mounted on the cutter bar 6. The pin lock 15 is rotatable into engagement with appropriately located notches 16 formed on the frame to lock the cutter bar in its different angular positions about its pivot. In the present construction the truck wheel driving member 8 is in the form of a chain sprocket and is connected to the truck wheels 2 by an endless chain 17 engaging a sprocket 18 fixed to the rear truck wheel axle, while the front and rear axles are connected in driving relation by a chain and sprocket connection 19.

Now referring to the cutter chain drive, it will be noted that supported within the frame 4 is a motor having a power shaft 20 horizontally disposed and extending longitudinally of the machine. As shown in Fig. 3, aligned with the shaft 20 and connectible thereto by a sliding clutch 21 is a shaft 22 driving a bevel pinion 23 meshing with a bevel gear 24. Driven by the gear 24 is a spur pinion 25 meshing with a large spur gear 26 connected in driving relation with a chain sprocket 27 engaging and driving the cutter chain 7 in a well known manner.

The improved plural speed transmission mechanism for driving the members 8 and 9 in either of opposite directions at high and low speeds comprises, as shown in Figs. 4 and 6, a spur pinion 28 fixed to the rear end of the motor shaft 20 and meshing with a spur gear 29. The spur gear 29 meshes with spur gears 30 and 31 respectively fixed to parallel horizontal shafts 32 and 33 disposed on longitudinally extending axes 50

spaced equi-distantly from the longitudinal vertical center of the machine. The plural speed driving connections for effecting bar swing and truck wheel drive at high and low speeds in one direction are driven from the shaft 33 and the low speed gearing comprises a worm 34 fixed to the shaft 33 and meshing with a worm wheel 35 fixed to a vertical shaft 36. Fixed to the shaft 36 is a worm 37 meshing with a slow speed worm wheel 38 connectible by a multiple disc clutch 39 and an interlocking mechanism 40 to a horizontal shaft 41 extending transversely of the machine frame and suitably journaled therein. The high speed gearing comprises a worm 42 fixed to the shaft 33 and meshing with a high speed worm wheel 43 connectible by a multiple disc clutch 44 and the interlocking mechanism 40 to the shaft 41. The plural speed gearing for effecting bar swing and truck wheel drive at high or low speeds in the reverse direction is driven from the shaft 32 and is similar in construction to the plural speed mechanism described above. The slow speed gearing comprises a worm 45 fixed to the shaft 32 and meshing with a worm wheel 46 fixed to a vertical shaft 47. Also fixed to the shaft 47 is a worm 48 meshing with a slow speed worm wheel 49 connectible by a multiple disc clutch 50 and an interlocking mechanism 51 to the shaft 41. The high speed gearing comprises a worm (not shown), similar to the worm 42 but having teeth of opposite lead, meshing with a high speed worm wheel 52 connectible by a multiple disc clutch 53 and the interlocking mechanism 51 to the shaft 41. It will thus be seen that when one or the other of the disc clutches 44, 39 is applied and the interlocking mechanism 40 is connected, the shaft 41 may be driven at either a high or a low speed in one direction, and when the clutches 39, 44 and the interlocking connection 40 are released and one or the other of the disc clutches 53, 50 is applied, and the interlocking connection 51 is connected, the shaft 41 may be driven at either a high or a low speed in the reverse direction. As shown in Fig. 4, the members 8 and 9 are rotatably supported by the shaft 41 and are alternatively connectible in driving relation with the shaft by means of sliding clutches 54 and 55 respectively. The clutches 54, 55 are provided with operating handles 56 and 57 respectively and are connected together by means of an actuating rod 58 extending centrally through the shaft 41. It will thus be seen that when one clutch is connected the other clutch is maintained released. The interlocking mechanisms 40 and 51 and the control mechanism for the multiple disc clutches will now be described. Now referring to the operating means for the multiple disc clutches 39 and 44, it will be noted that interposed between the clutches and surrounding the shaft 41 is a clutch applying member 59 with which a shipper yoke 60, pivoted at 61 on the frame, operates. This shipper yoke has a lateral arm 62 projecting within a notch or recess 63 formed in a slidably actuating rod 64. This rod is slidably guided at its inner end within a bore 65 formed in a bracket 66 suitably attached to the frame, and this rod is threaded at 67 throughout a portion of its length and is connected to a rotatable adjusting nut 68. Formed on this nut is a bevel gear 69 meshing with a bevel gear 70 fixed to a longitudinally extending shaft 71 rotatably supported within the frame. Secured to the outer end of this shaft is an operating handle 72. The multiple disc clutches 50, 53, are pro-

vided with similar control mechanism including a clutch applying member 73, pivoted shipper yoke 74, reciprocable actuating rod 75, threaded nut 76, bevel gears 77, 78 and operating handle 79. The clutch applying members 59 and 73 are each connected through an anti-friction bearing 80 to an annular clutch member 81 slidably mounted on an enlarged cylindrical portion 82 formed on a hollow shaft 83 suitably journaled within the frame and through which shaft 41 extends. The end surfaces of the member 81 are adapted to engage plungers 84 carried within the adjacent vertical end plates of the worm wheels. When the clutch applying member is shifted in one direction or the other, one or the other of the sets of plungers is engaged, thereby to effect application of the clutches. It will thus be seen that when the clutch operating handle is rotated, rotation of the nut imparts axial movement to the actuating rod in one direction or the other to swing the shipper yoke about its pivot, and as a result, the clutch applying member, together with the member 81, are shifted into one or the other of their operating positions.

As the interlocking mechanisms 40 and 51 are identical in structure, the description of the mechanism 40 will suffice for both. As shown, the clutch member 81 is internally grooved at 85 and is provided with oppositely disposed cam surfaces 86. Projecting within the groove 85 in the clutch member, when the latter is in the position shown in Fig. 4, are clutch plungers 87 slidably mounted within radial chambers 88 formed in the enlarged portion 82 of the hollow shaft 83. The plungers 87 are constantly urged into their outer released positions by coil springs 89. The inner ends of the plungers, when in the position shown in Fig. 7, engage slots or grooves 90 cut in the shaft 41. Each of the clutch plungers is provided with an inclined surface which is complementary to the cam surface 86 on the clutch member 81. When the parts are in the position shown in Fig. 4, the clutch plungers of the interlocking mechanism 40 are held by the coiled springs within the annular recess 85 in the member 81 with their inner ends wholly released from the grooves in the shaft 41. When the clutch member 59 is in this position, the disc clutches 39 and 44 are both released. At this time the shaft 41 may rotate freely relative to the drive mechanism, the shaft, upon rotation thereof, turning freely within the hollow shaft 83. However, when the clutch applying member 59 is moved toward a position to apply one of the disc clutches, the cam surfaces 86 force the plungers 87 into an interlocking engagement with the grooves on the shaft 41, thereby connecting the hollow shaft 83 to the shaft 41 in the manner shown in Fig. 7. Heretofore it has been found that without the provision of the interlocking clutch plungers between the hollow shaft 83 and the shaft 41, drag rotation was imparted by the clutch discs even when the latter were in their released position, which caused the shaft 41 to rotate, but by the provision of these plungers, such drag rotation is entirely eliminated.

To prevent simultaneous application of any of the clutches, together with possible damage to the mechanism, there is provided an interlock mechanism between the clutch actuating rods 70 and 75, as shown in Fig. 5. This interlock mechanism comprises a slide member 91 suitably guided on the frame and having an operating handle 92. The opposite ends of this slide member are provided with cam surfaces 93 which are 75

engageable with a pair of plungers 94 which are in turn engageable with notches 95 formed on the actuating rods. When the slide member is in the position shown in Fig. 5, the actuating rod 5 64 is locked against movement by one of the plungers 94, while due to the position of the cam surfaces 93, the other plunger 94 is in its released position so that the actuating rod 75 is released. When the slide is moved into its opposite position, the rod 75 is held against movement while the rod 94 is released.

In the use of the improved mining machine, when the clutch 55 is released and the clutch 54 is connected and the high speed clutch 44 is applied, the mining machine may be moved along the mine trackway under the propulsion of the truck wheels at a relatively high speed. When the clutch 44 is released and the clutch 53 is applied, the mining machine may be moved along 10 the mine trackway in the reverse direction at a high speed. Upon disconnection of the clutch 54 and connection of the clutch 55, when one or the other of the friction clutches 44 and 53 is applied, the cutter bar may be swung about its pivot in either of opposite directions at a high speed. When the clutches 44, 53 are released and one or the other of the clutches 39 and 50 is applied, the cutter bar may be swing about its pivot in either of opposite directions at a relatively slow speed. To effect propulsion of the mining machine along the mine trackway at a slow cutting speed to effect sumping of the cutter bar in the coal, the slow speed clutch 39 is applied and reversal of the machine at a slow speed to effect withdrawal of the cutter bar is effected by the application of the slow speed reverse clutch 50. As the mode of operation of a mining machine of the arc-cutter type is well known to those skilled in the art, a further description of the mode of operation of the machine is thought unnecessary. Other uses and advantages of the improved mining machine will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a portable base, kerf cutting mechanism thereon including a swingable kerf cutter, and mechanism for swinging said kerf cutter relative to said base including a plural speed transmission mechanism for effecting swinging of the kerf cutter at fast and slow speeds in one direction, a separate fast and slow speed transmission mechanism for effecting swinging of the kerf cutter at fast and slow speeds in the opposite direction, the terminal driving elements of said transmission mechanisms arranged on horizontal axes, and base propelling means operable through said transmission mechanisms.

2. In a mining machine, a portable base, kerf cutting mechanism thereon including a swingable kerf cutter, and mechanism for swinging said kerf cutter about its pivot relative to said base including a fast and slow speed transmission gearing for effecting swinging of the kerf cutter at fast and slow speeds, a separate fast and slow speed transmission gearing for also effecting kerf cutter swing about said pivot at fast and slow

speeds, the terminal driving elements of said transmission gearings arranged on horizontal axes, and base propelling means operable through said transmission gearings.

3. In a mining machine, a portable base, kerf cutting mechanism thereon including a swingable kerf cutter, and mechanism for swinging said kerf cutter relative to said base including a fast and slow speed transmission gearing for effecting swinging of the kerf cutter at fast and slow speeds in one direction, a separate and distinct fast and slow speed transmission gearing for effecting kerf cutter swing at fast and slow speeds in the opposite direction, the terminal driving elements of said transmission gearings arranged on horizontal axes, and base propelling means operable through said transmission gearings.

4. In a mining machine, a portable base, kerf cutting mechanism thereon including a swingable kerf cutter, mechanism for propelling said base including a machine propelling member, and mechanism for swinging said kerf cutter relative to said base including a kerf cutter swinging member, said propelling mechanism and said kerf cutter swinging mechanism including a plural speed transmission mechanism for driving said members at high and low speeds in one direction, and a separate and distinct plural speed transmission mechanism for driving said members at high and low speeds in the reverse direction.

5. In a mining machine, a portable base, kerf cutting mechanism on said base, and machine propelling mechanism including a propelling member arranged with its axis lying in a vertical plane extending transversely of the machine and a plural speed transmission mechanism for driving said propelling member at high and low speeds in one direction and a separate and distinct plural speed transmission mechanism for driving said propelling member at high and low speeds in the reverse direction.

6. In a mining machine, a portable base, kerf cutting mechanism thereon including a swingable kerf cutter, mechanism for swinging said kerf cutter relative to said base, and mechanism for propelling the machine, said kerf cutter swinging mechanism and said machine propelling mechanism including a plural speed transmission mechanism for effecting drive thereof at high and low speeds in one direction and a separate and distinct plural speed transmission mechanism for effecting drive thereof at high and low speeds in the reverse direction.

7. In a mining machine, a portable base, kerf cutting mechanism thereon including a swingable kerf cutter, mechanism for swinging said kerf cutter including a kerf cutter swinging member adapted to cooperate directly with flexible kerf cutter swinging means, and mechanism for propelling the machine including a machine propelling member adapted to cooperate directly with flexible machine propelling means, a mechanism for driving said members at high and low speeds in one direction and a separate and distinct mechanism for driving said members at high and low speeds in the reverse direction.

8. In a mining machine, kerf cutting mechanism including a swingable kerf cutter, and mechanism for swinging said kerf cutter about its pivot including a transmission mechanism for effecting swinging of the kerf cutter at a slow cutting speed in one direction, a separate and distinct transmission mechanism for effecting swinging of the kerf cutter at a slow cutting speed in the opposite direction, the terminal

elements of said transmission mechanisms arranged on horizontal axes, and machine propelling means operable through said transmission mechanisms.

5. 9. In a mining machine, kerf cutting mechanism including a swingable kerf cutter, and mechanism for swinging said kerf cutter about its pivot including a transmission mechanism for effecting swinging of the kerf cutter at a slow

10 cutting speed and at a high positioning speed in one direction, a separate and distinct transmission mechanism for effecting swinging of the kerf cutter at a slow cutting speed in the opposite direction, the terminal elements of said transmission mechanisms arranged on horizontal axes, and machine propelling means operable through said transmission mechanisms.

15 10. In a mining machine, kerf cutting mechanism including a swingable kerf cutter, and

20 mechanism for swinging said kerf cutter about its pivot including a transmission mechanism for effecting swinging of the kerf cutter at a slow cutting speed in one direction, a separate and distinct transmission mechanism for effecting

25 swinging of the kerf cutter at a slow cutting and at a high positioning speed in the opposite direction, the terminal elements of said transmission mechanisms arranged in horizontal axes, and machine propelling means operable through said transmission mechanisms.

30 11. In a mining machine, machine propelling means including a propelling member arranged with its axis lying in a vertical plane extending transversely of the machine, a plural predetermined speed transmission mechanism for driving said propelling member at a plurality of speeds in one direction, and a separate and distinct plural predetermined speed transmission mechanism for driving said propelling member

35 at the same speeds in the reverse direction.

40 12. In a mining machine, machine propelling means including a propelling member arranged with its axis lying in a vertical plane extending transversely of the machine, a transmission mechanism for driving said propelling member at a low speed and at a relatively high speed in one direction, and a separate and distinct transmission mechanism for driving said propelling member at the same speeds in the reverse direction.

45 13. In a mining machine, machine propelling means including a propelling member arranged with its axis lying in a vertical plane extending transversely of the machine, a plural predetermined speed transmission mechanism for driving said propelling member at a plurality of speeds in one direction, and a separate and distinct plural predetermined speed transmission mechanism for driving said propelling member at the same speeds and including a relatively

50 high speed in the opposite direction.

55 14. In a mining machine, kerf cutting mechanism including a swingable kerf cutter having its pivot disposed at right angles to the plane of swinging movement thereof, machine propelling means including a propelling member, a common transmission mechanism for effecting kerf cutter swing and drive of said propelling member at a low cutting speed in one direction, and a separate and distinct transmission mechanism for effecting

60 swinging of the kerf cutter and drive of the propelling member both at a low cutting speed in the reverse direction.

65 15. In a mining machine, kerf cutting mechanism including a swingable kerf cutter having its pivot disposed at right angles to the plane of

70 swinging movement thereof, machine propelling means including a propelling member, a common transmission mechanism for effecting kerf cutter swing and drive of said propelling member at a low cutting speed and a relatively high speed in one direction, and a separate and distinct transmission mechanism for effecting swinging of the kerf cutter and drive of the propelling member both at a low cutting speed in the reverse direction.

5

10

15 16. In a mining machine, kerf cutting mechanism including a swingable kerf cutter having its pivot disposed at right angles to the plane of swinging movement thereof, machine propelling means including a propelling member, a common transmission mechanism for effecting kerf cutter swing and drive of said propelling member at a low cutting speed in one direction, and a separate and distinct transmission mechanism for effecting swinging of the kerf cutter and drive of the propelling member both at a low cutting speed and at a relatively high speed and in the reverse direction at either speed.

15

20 17. In a mining machine, kerf cutting mechanism including a swingable kerf cutter, machine propelling means including a propelling member, separate and distinct fast and slow speed transmission mechanisms each including fast and slow speed driving gearing and each operative either to drive the propelling means or to swing the kerf cutter, and means for only alternatively effecting swing of the kerf cutter and drive of the propelling member through said transmission mechanisms.

25

30 18. In a mining machine, kerf cutter feeding mechanism including a shaft arranged with its axis lying in a vertical plane extending transversely of the machine, a fast and slow speed transmission mechanism for driving said shaft at predetermined fast and slow speeds in one direction, and a separate and distinct fast and slow speed transmission mechanism for driving said shaft at predetermined fast and slow speeds in the reverse direction.

40

45 19. In a mining machine, kerf cutter feeding mechanism including a shaft arranged with its axis lying in a vertical plane extending transversely of the machine, a fast and slow speed transmission mechanism for driving said shaft at predetermined fast and slow speeds in one direction, and a separate and distinct fast and slow speed transmission mechanism for driving said shaft at predetermined fast and slow speeds in the reverse direction, kerf cutter feeding elements, and means operable at will for selectively connecting said elements in driving relation with said shaft.

45

50 20. In a mining machine, kerf cutter feeding mechanism including a shaft, a fast and slow speed transmission mechanism for driving said shaft at predetermined fast and slow speeds in one direction, and a separate and distinct fast and slow speed transmission mechanism for driving said shaft at predetermined fast and slow speeds in the reverse direction, each transmission mechanism including a driving element coaxial with said shaft, and operator-controllable interlocking clutch mechanism for alternatively connecting said driving elements to said shaft.

60

65 21. In a mining machine, kerf cutter feeding mechanism including a shaft, a fast and slow speed transmission mechanism for driving said shaft at predetermined fast and slow speeds in one direction, and a separate and distinct fast and slow speed transmission mechanism for driv-

75

ing said shaft at predetermined fast and slow speeds in the reverse direction, each transmission mechanism including relatively rotatable fast and slow speed terminal gears coaxial with said shaft, and clutch mechanism operable at will for selectively rendering said gears effective to drive said shaft.

22. In a mining machine, kerf cutter feeding mechanism including a shaft, a fast and slow speed transmission mechanism for driving said shaft at predetermined fast and slow speeds in one direction, and a separate and distinct fast and slow speed transmission mechanism for driving said shaft at predetermined fast and slow speeds in the reverse direction, each transmission mechanism including relatively rotatable fast and slow speed terminal gears coaxial with said shaft, clutch mechanism operable at will for selectively rendering said gears effective to drive said shaft, and operator-controllable interlocking clutch mechanism in the drive between said driving gears and said shaft.

23. In a mining machine, kerf cutter feeding mechanism including a shaft, a fast and slow speed transmission mechanism for driving said shaft at predetermined fast and slow speeds in one direction, and a separate and distinct fast and slow speed transmission mechanism for driving said shaft at predetermined fast and slow speeds in the reverse direction, each transmission mechanism including relatively rotatable fast and slow speed terminal gears coaxial with said shaft, clutch mechanism operable at will for selectively rendering said gears effective to drive said shaft, and operator-controllable interlocking clutch mechanism in the drive between said driving gears and said shaft, said interlocking clutch mechanism always being connected prior to the connection of said first mentioned clutch mechanism.

40 24. In a mining machine, kerf cutter feeding mechanism including a shaft, connections between said shaft and the kerf cutter, and driving mechanism for said shaft including a fast and slow speed transmission mechanism and a separate and distinct fast and slow speed transmission mechanism, each transmission mechanism including fast and slow speed terminal gears individual thereto and arranged coaxial with said shaft, and means operable at will for selectively connecting said gears in driving relation with said shaft.

25 25. In a mining machine, kerf cutter feeding mechanism including a shaft, connections between said shaft and the kerf cutter, separate fast and slow speed transmission mechanisms, each transmission mechanism having fast and slow speed terminal gears individual thereto coaxial with said shaft, individual clutches controlling the transmission of power by each terminal gear, operator-controllable interlocking clutch mechanism between said terminal gears and said shaft, relatively rotatable feeding elements coaxial with said shaft, and clutch mechanism operable at will for selectively connecting said feeding elements to said shaft.

65 26. In a mining apparatus, a wheeled truck adapted to run along a mine trackway, kerf cutting mechanism on said truck including a swingable kerf cutter, propelling means for said truck including a propelling member, and common motor operated mechanism for independently swinging said kerf cutter and driving said propelling member at either of two relatively different speeds and in either direction at either speed, said motor operated mechanism including speed changing

and reversing mechanism, speed changing and reversing elements of which are arranged on a common axis.

27. In a mining apparatus, a wheeled truck adapted to run along a mine trackway, kerf cutting mechanism on said truck including a swingable kerf cutter, propelling means for said truck including a propelling member, common motor operated mechanism for independently swinging said kerf cutter and driving said propelling member at either of two relatively different speeds and in either direction at either speed, said motor operated mechanism including speed changing and reversing mechanism, speed changing and reversing elements of which are arranged on a common axis, and means operable at will for separately but not simultaneously connecting said kerf cutter swinging and truck propelling means in driving relation with said motor operated mechanism.

28. In a mining machine, a portable base, kerf cutting mechanism thereon including a swingable kerf cutter, and mechanism for swinging said kerf cutter relative to said base including a plural speed transmission mechanism for effecting swinging of the kerf cutter at fast and slow speeds in one direction, a separate fast and slow speed transmission mechanism for effecting swinging of the kerf cutter at fast and slow speeds in the opposite direction, and base propelling means operable through said transmission mechanisms.

29. In a mining machine, a portable base, kerf cutting mechanism thereon including a swingable kerf cutter, and mechanism for swinging said kerf cutter relative to said base including a fast and slow speed transmission gearing for effecting swinging of the kerf cutter at fast and slow speeds, a separate fast and slow speed transmission gearing for also effecting kerf cutter swing at fast and slow speeds, and base propelling means operable through said transmission gearings.

30. In a mining machine, a portable base, kerf cutting mechanism thereon including a swingable kerf cutter, and mechanism for swinging said kerf cutter relative to said base including a fast and slow speed transmission gearing for effecting swinging of the kerf cutter at fast and slow speeds in one direction, a separate and distinct fast and slow speed transmission gearing for effecting kerf cutter swing at fast and slow speeds in the opposite direction, and base propelling means operable through said transmission gearings.

35 31. In a mining machine, kerf cutting mechanism including a swingable kerf cutter, and mechanism for swinging said kerf cutter about its pivot including a transmission mechanism for effecting swinging of the kerf cutter at a slow cutting speed in one direction, a separate and distinct transmission mechanism for effecting swinging of the kerf cutter at a slow cutting speed in the opposite direction, and machine propelling means operable through said transmission mechanisms.

32. In a mining machine, kerf cutting mechanism including a swingable kerf cutter, and mechanism for swinging said kerf cutter about its pivot including a transmission mechanism for effecting swinging of the kerf cutter at a slow cutting speed and at a high positioning speed in one direction, a separate and distinct transmission mechanism for effecting swinging of the kerf cutter at a slow cutting speed in the opposite direction, and machine propelling means operable through said transmission mechanisms.

33. In a mining machine, kerf cutting mechanism including a swingable kerf cutter, and mechanism for swinging said kerf cutter about its pivot including a transmission mechanism for effecting swinging of the kerf cutter at a slow cutting speed in one direction, a separate and distinct transmission mechanism for effecting swinging of the kerf cutter at a slow cutting and at a high positioning speed in the opposite direction, and machine propelling means operable through said transmission mechanisms. 5
34. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 10
35. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 15
36. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 20
37. In a mining apparatus, a wheeled truck adapted to run along a mine trackway, kerf cutting mechanism on said truck including a swingable kerf cutter, a kerf cutter swinging sprocket arranged at the rear end of said truck and having cooperating directly therewith a flexible swinging element connected to said kerf cutter, a truck propelling sprocket arranged at the rear end of said truck and having a cooperating flexible connection with the truck wheels, and motor operated mechanism for independently driving said kerf cutter swinging sprocket and said propelling sprocket at either of two relatively different speeds and in either direction at either speed. 25
38. In a mining apparatus, a wheeled truck adapted to run along a mine trackway, kerf cutting mechanism on said truck including a swingable kerf cutter, a kerf cutter swinging sprocket arranged at the rear end of said truck and having cooperating directly therewith a flexible swinging element connected to said kerf cutter, a truck propelling sprocket arranged at the rear end of said truck and having a cooperating flexible connection with the truck wheels, motor operated mechanism for independently driving said kerf cutter swinging sprocket and said propelling sprocket at either of two relatively different speeds and in either direction at either speed, and means operable at will for separately but not simultaneously connecting said kerf cutter swinging sprocket and said truck propelling sprocket in driving relation with said motor operated mechanism. 30
39. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 35
40. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 40
41. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 45
42. In a mining apparatus, a wheeled truck adapted to run along a mine trackway, kerf cutting mechanism on said truck including a swingable cutter and a cutter bar swinging member, propelling means for said truck including a propelling member operatively connected to the truck wheels, and motor operated mechanism for independently driving said bar swinging and propelling members at either of two relatively different speeds including a horizontal shaft extending transversely of said truck, operator-controllable clutch means for connecting either said bar swinging member or said propelling member in driving relation with said transverse shaft, fast and slow speed gear trains each having a final terminal worm wheel coaxial with said shaft, worms rotating on parallel longitudinally extending axes and meshing with said worm wheels, and operator-controllable clutch means for selectively connecting said terminal worm wheels to said shaft. 50

MORRIS P. HOLMES.

CERTIFICATE OF CORRECTION.

Patent No. 1,996,765.

April 9, 1935.

MORRIS P. HOLMES.

It is hereby certified that error appears in the printed specification of the above numbered patent requiring correction as follows: Page 4, first column, line 28, claim 10, for "in" read on; and page 5, first column, line 14, claim 22, for "predetrmined" read predetermined; and that the said Letters Patent should be read with these corrections therein that the same may conform to the record of the case in the Patent Office.

Signed and sealed this 11th day of June, A. D. 1935.

(Seal)

**Leslie Frazer
Acting Commissioner of Patents.**
